US0D1113346S

(12) **United States Design Patent** (10) **Patent No.:** **US D1,113,346 S**
(45) **Date of Patent:** **** Feb. 17, 2026**

(54) **BOTTLE**

(71) Applicant: **YETI Coolers, LLC**, Austin, TX (US)

(72) Inventors: **Dustin R. Bullock**, Austin, TX (US); **Colin Darling**, Austin, TX (US); **Evan Goldberg**, Austin, TX (US); **Hector Barea**, Austin, TX (US); **Melissa Cosler**, Austin, TX (US)

(73) Assignee: **YETI Coolers, LLC**, Austin, TX (US)

(**) Term: **15 Years**

(21) Appl. No.: **29/860,617**

(22) Filed: **Nov. 21, 2022**

Related U.S. Application Data

(63) Continuation of application No. 29/857,966, filed on Oct. 26, 2022.

(51) **LOC (15) Cl.** **07-01**

(52) **U.S. Cl.**

USPC **D7/510**

(57) **CLAIM**

The ornamental design for a bottle as shown and described.

DESCRIPTION

FIG. 1 is a top, front, left perspective view of a bottle showing our new design;

FIG. 2 is a bottom, rear, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depicting the remainder of the bottle form no part of the claimed design.

1 Claim, 7 Drawing Sheets
